FLUID ACTUATED INJECTION MEANS

Louis J. Garday, Glenview, and Robert A. Lasley,
Chicago, Ill., assignors, by means assignments,
to Louis G. Simmons, Chicago, Ill.

Application October 11, 1945, Serial No. 621,720

18 Claims. (Cl. 103—44)

1 This invention relates to liquid injection systems and controls therefor, more particularly to pumps and control means for the injection of fuel into internal combustion engines, and it is an object of the invention to provide improved injection means of this character.

While the invention is especially adapted for use in and is illustrated in connection with an engine of the Diesel or compression ignition type, it will be apparent to those skilled in the art that modifications may be made to adapt the invention for use in connection with any engine or apparatus requiring the injection of a measured or predetermined amount of high pressure fuel or liquid without departing from the true spirit and scope of the invention.

It is an object of the invention to provide a fluid pressure actuated injection pump for supplying positively metered quantities of liquid from a high pressure source.

It is a further object of the invention to provide a fluid pressure actuated fuel injection pump of the character indicated in which the engine fuel supply is the source of fluid pressure.

It is another object of the invention to provide a fuel injection pump of the character described having means within the fuel injection pump for automatically refilling the metering chamber with fuel from the high pressure source.

In the embodiment shown, a pump unit is provided with a cylindrical chamber in which a movable wall or piston is arranged, the chamber on one side of the piston communicating with a fuel injection nozzle and the chamber on the other side of the piston communicating with a source of fuel under pressure through a suitably arranged valve. A passageway with a valve for opening and closing the passageway interconnects the chambers on the two sides of the piston and a spring biases the piston against fuel injection. Fuel injection is produced by the engine cam actuating a plunger which substantially simultaneously closes the valve in the interconnecting passageway and opens the fuel inlet valve whereupon the high pressure fuel acting against one side of the piston moves the piston to effect the ejection of fuel from the chamber on the other side of the piston through the injection nozzle. Return of the plunger to its original position closes the fuel inlet valve and opens the valve in the interconnecting passageway, allowing the pressure to equalize on the two sides of the piston, whereupon the spring moves the piston to its original position forcing fuel into the metering chamber through the interconnecting passageway.

It is a further object of the invention to provide a fuel injection pump of the character described whereby secondary injection of fuel is substantially prevented.

2 For a more complete understanding of the invention, reference should be had to the drawings, in which:

Fig. 1 is a schematic representation of a portion of a Diesel engine partially in section embodying the invention, assembled for operation;

Fig. 2 is a detailed sectional view of one embodiment of the invention;

Fig. 3 is an elevational view of a portion of the invention in assembled relation;

Fig. 4 is a plan view of the invention in assembled relationship;

Fig. 5 is a detailed sectional view taken substantially along line 5—5 of Fig. 2 showing the regulating mechanism;

Fig. 6 is a detailed sectional view of a further embodiment of the invention; and

Figs. 7, 8, 9, 10 and 11 are schematic representations of the basic elements of the invention illustrating the mode of operation.

Referring now to the drawings, the invention is shown as embodied in a Diesel engine 10 having a common rail type of fuel injection system, it being noted that the description of the invention as embodied in a Diesel engine is merely exemplary. Fuel under high pressure is supplied from the rail or conduit 11 through a conduit 12 to the inlet 12a of the fuel injection pump 13, the valve actuation to produce fuel injection being effected by an engine operated cam 14, cam follower 15, push rod 16 and tappet mechanism 17, and throttle control being effected by rack 18 actuated by a crank 19 which may be adjusted on its operating shaft 20 by bolts 20a. Although only a single cylinder and fuel injection pump is shown, it will be understood that the engine 10 includes a plurality of cylinders and a corresponding number of fuel injection pumps fed from the common rail 11.

Referring now to Fig. 2, the fuel injection pump comprises a body 21 including a fuel injection nozzle 22 through which fuel is injected into the engine, the injection being controlled by a needle valve 23 held in the closed position by means of a valve stem 24 and a spring 25, the amount of nozzle opening being determined by a stop screw 27 shown susceptible of external adjustment.

The body 21 is provided with a longitudinal bore 28 in which are axially mounted suitable timing valve bodies 29 and 30 and a timing plunger body 31 spaced axially from the timing valve body 29 by a suitable sealing gasket 32, the timing valve bodies and timing plunger body being retained and sealed in position by suitable sealing means 34 and 35. The timing valve body 29 is provided with a longitudinal bore 36, an enlarged bore 37 communicating with the bore 36, and a circumferential cut-away portion cooperating with a similar circumferential cut-away portion on timing valve body 30 to form

circumferential groove 38. The timing valve body 38 is also provided with a longitudinal bore 38, an enlarged bore 48 communicating therewith, and a passageway 33 connecting the bore 48 and the circumferential groove 38. A timing valve 41, arranged to slide in the longitudinal bore 38, has flutes 42 machined on its outer surface to provide a passageway for fuel and has an enlarged head movable in a bore 43 in the body 21 communicating with the bore 38. The head of the valve 41 cooperates with a suitable valve seat provided on the timing valve body 28 as shown, the valve being normally held in closed position by a spring 44 in bore 43. A timing valve 45, which is generally similar to the timing valve 41, slides in the longitudinal bore 38, the head of the valve 45 moving within the bore 37 and being in contact with the valve 41 so that closing of valve 45 is also produced by spring 44, an appropriate valve seat being provided on valve body 30 as shown.

The timing plunger body 31 is provided with a bore 50 connected by radial holes 51 with a circumferential groove 52 which communicates with a passageway 53a leading to the fuel nozzle 22. A timing plunger 54 biased by a spring 56 against a timing adjustment screw 55 threaded in the retainer body 34a slides in the bore 50 under the influence of the timing plunger pin 58 which is actuated by an engine cam as indicated above. The timing plunger 54 is provided at one end thereof with an axial hole 57 communicating through radial holes 58 with a circumferential groove as shown which registers with the radial holes 51 in the body 31. It will be seen that the axial hole 57 communicates with a chamber 47 formed by the end of timing plunger 54, the bore 50 in timing plunger body 31 and the adjacent end of timing valve 45, the chamber being variable in volume with the position of timing plunger 54 and communicating with the enlarged bore 48 of timing valve body 38 and thence with the circumferential groove 38 for a purpose to be described hereinafter.

The body 21 also includes a bore 60 in which is threaded a metering shaft guide 61 to position and seal in the bore, by means of a gasket 62, a metering stop guide 63 axially abutting a metering plunger barrel 64 which axially abuts a metering plunger stop plate 65. Within the bore 66 of the metering plunger barrel 64 there is a fuel piston or metering plunger 67 biased by a spring 68 against a metering stop 69, the spring 68 being seated on a spring seat 10 rotatable on a steel ball 71 bearing on the spring plate 72 to prevent any distortions from occurring in the spring 68 as a result of rotating the metering plunger 67. The spring plate 72 has openings 73 connecting the fuel ejection chamber 14 formed by the plunger 67 in the bore 66 with the passageway 53 leading to the fuel injection nozzle 22.

The metering plunger barrel 64 has an enlarged bore 76 at one end thereof cooperating with the metering plunger 67, the metering stop 69 and the metering stop guide 63 to form a piston actuating chamber 77, connected by radial holes 78 in the metering plunger barrel 64 with a circumferential groove 79 which is in turn connected by a passageway 78 with the circumferential groove 38. It will be seen that with the timing valves 41 and 45 in the closed position and with the timing plunger 54 engaging the stop screw 55 there is a passageway between the chamber 47 and the chamber 77. With the timing valves 41 and 45 completely open, the timing

plunger will be in its extreme right-hand position, the radial holes 51 will be closed by the outer surface of the timing plunger 54 and hence there will be communication from the fuel inlet 12a to the plunger actuating chamber 77.

The initial position of the metering plunger 67 and hence the amount of fuel injected into the engine cylinder at each operation is determined by the position of the metering stop 69 which is adjustable by means of threads in the metering stop guide 63 through the metering shaft 81 which is splined to metering stop 69 by splines 82 as shown.

The metering shaft 81 is rotatably supported in the bore 83 of the metering shaft guide 61 and is rotated by means of rack 84 movably supported in a bore 85 in the body 21 and having teeth 84 engaging a gear 86 connected to the metering shaft 81 by a Woodruff key 87, the key 87 being fixed to the gear 86 by a pin 88, thereby preventing relative movement of the metering shaft 81 and gear 86.

By the above described arrangement of the metering shaft 81, the gear 86, the Woodruff key 87 and the pin 88, the gear 86 and metering shaft 81 may be accurately positioned even though the gear and shaft are hardened. Drilling of the gear and shaft before hardening as well as after hardening is impractical due to necessity of accurately determining the final position of shaft and gear. However, the metering shaft 81 may be machined before hardening and the gear 86 may be drilled before hardening, the Woodruff key 87 then being the only part to be drilled to complete the assembly and this may be done after hardening while the gear and shaft are held in the desired position.

To take the thrust exerted against the end of the metering shaft by the high fluid pressure, a thrust screw 90 threaded in a cover 91 supports a steel ball 93 against the end of the metering shaft as shown.

In Fig. 6 there is shown an embodiment of the invention in which the pump actuating mechanism is axially disposed with respect to the fuel nozzle 22. The admission of fuel from the fuel inlet 12a is controlled by a disk valve 95 seated on an appropriate valve seat in valve body 28 and separated from a second disk valve 96 by a fluted spacer 97, actuation of the disk valves 95 and 96 being effected through a fluted slide 98 by the timing plunger 54. In other respects the embodiment of Fig. 6 is similar to that shown in Fig. 2.

Fuel under high pressure is supplied through the conduit 12, all of the chambers and passageways being filled with fuel and it is thought that the operation of the pump may best be understood by referring to the diagrammatic illustrations of Figs. 7, 8, 9, 10 and 11, in which reference numerals corresponding to those of Fig. 2 are used. Referring first to Fig. 11, the parts of the pump 13 are shown in the normal or inoperative position with high pressure fuel available in conduit 12, the valve 41 (corresponding to valves 41 and 45 of Fig. 2) being closed and the timing plunger 54 being against its stop 55 (Fig. 2). The piston actuation chamber 77 is in communication with the fuel ejection chamber 14 through the passageways 53 and 78, the chamber 47 and the passageway 53a, the pressures in chambers 14 and 77 thus being equal, and the spring 68 maintains the metering plunger 67 against its stop 69, the position of stop 69 having been adjusted to give the desired amount

of fuel injection for the desired engine load and speed. The pressure of the fuel in the various chambers and passageways is relatively low and is not sufficient to raise the needle valve 23 from its seat in the injection nozzle 22.

In Fig. 7, the engine driven cam 14, through the appropriate mechanism as illustrated, is shown as having moved the timing plunger 54 sufficiently to close off the radial holes 51 from the radial holes 58, thereby disconnecting the passageway 53a from chamber 47 and also as having partially opened the valve 41, allowing high pressure fuel to enter the plunger actuating chamber 77 as shown by the arrows, beginning movement of the plunger 67. The fuel in the ejection chamber 74 is under high pressure as a result of the plunger movement but it is not sufficiently high to cause ejection of fuel from nozzle 22. In Fig. 8 the valve 41 has opened further and the plunger 67 has moved sufficiently under the high pressure fuel to increase the pressure in passageway 53, thereby raising the needle valve 23 off its seat to forcibly eject the fuel from nozzle 22.

With the conditions as shown in Fig. 9, the engine cam 14 has moved past its maximum position and the plunger 67 has completed the ejection of the fuel, the plunger being against its stop plate 65. Immediately prior to the condition of the system shown in Fig. 9 and immediately following the condition of the system shown in Fig. 8, the valve 41 will be closed but timing plunger 54 will still be in contact with the valve 41, and the metering plunger 67 will have completed the fuel injection. Consequently there is high pressure existing in the piston actuating chamber 77 and the passageway leading to chamber 47 since these chambers have been in communication with the fuel inlet 12a, and the fuel pressure in the chamber 74 and the passageway 53 is low due to the fuel injection.

If, under these conditions, the radial openings 51 were brought into registry with radial openings 58, the influence of the high pressure from the chamber 77 on the fuel in the chamber 74 and passageways 53 and 53a would cause a secondary injection of fuel from the nozzle 22 which is undesirable. To prevent this condition from occurring, the radial holes 58 are so placed relative to the end of the timing plunger 54 that the end of the plunger moves away from the valve 41 (Fig. 9) before bringing the radial holes 51 and 58 into registry, thereby increasing the volume of the chamber 47 and effectively relieving or reducing the high pressure in chamber 77. In Fig. 9 the increase in the volume of chamber 47 is indicated by the space between the right end of valve 41 and the left end of plunger 54. In Fig. 10 the timing plunger 54 is shown completely retracted and the radial holes 51 and 58 are in registry. The pressures in chambers 77 and 74 have been equalized through the passageways 75, 53 and 53a and the chamber 47, and the spring 68 has therefore begun to move the metering plunger 67 toward its stop 69, thereby forcing fuel from chamber 77 to chamber 74 as shown by the arrows to bring the system into condition for repeating its operation as shown in Fig. 11.

While particular embodiments of the invention are shown, it will be understood, of course, that it is not to be limited thereto since many modifications may be made, and it is therefore contemplated by the appended claims to cover any such modifications as fall within the true spirit and scope of the invention.

Having thus described the invention, what is claimed and desired to be secured by Letters Patent is:

1. The combination with a source of fluid under substantially constant pressure, of a cylinder, means in said cylinder forming a movable wall dividing said cylinder into two chambers, means for filling said two chambers with fluid from said source at a reduced pressure, means for applying the pressure of said fluid source on one side of said wall to move said wall and eject fluid from one of said chambers, and stop means for limiting the amount of movement of said wall during fluid ejection.
2. The combination with a source of fluid under substantially constant pressure, of a cylinder, means in said cylinder forming a movable wall dividing said cylinder into two chambers, means for filling said two chambers with fluid from said source at a reduced pressure, means for resiliently positioning said wall in said cylinder, means for applying the pressure of said fluid source on one side of said wall to move said wall against the force of said resilient means and eject the fluid from one of said chambers, and stop means for limiting the amount of movement of said wall during fluid ejection.
3. The combination with a source of fluid under substantially constant pressure, of a cylinder, means in said cylinder forming a movable wall dividing said cylinder into two chambers, means for filling said two chambers with fluid from said source, means for resiliently maintaining said wall in a predetermined position in said cylinder when the fluid in said chambers is at substantially equal pressure, means for applying the pressure of said fluid source on one side of said wall to move said wall against the force of said resilient means and eject the fluid from one of said chambers, stop means for limiting the amount of movement of said wall during fluid ejection, and means cooperating with said resilient means for returning said wall to said predetermined position and refilling said one chamber with said fluid.
4. A fluid pressure actuated fuel injection pump comprising a body having a chamber of variable volume adapted to be filled with fuel and having an ejection orifice, a piston movable in said chamber to eject fuel from said chamber through said orifice, rotatable stop means for positioning said piston to determine the volume of said chamber, fluid pressure means for moving said piston, means for causing the operation of said fluid pressure means, resilient means in said chamber biasing said piston against said stop means, and frictionless bearing means abutting one end of said resilient means to facilitate operation of said stop means.
5. A fluid pressure actuated injection pump comprising a body having a cylindrical bore therein, a piston movable in said bore and defining a pair of chambers, an inlet for high pressure liquid communicating with one of said pair of chambers, the other of said pair of chambers having an ejection orifice, a passageway interconnecting said chambers, normally open valve means for closing said passageway, normally closed valve means for opening said inlet, and means for operating said valves substantially simultaneously.
6. A fluid pressure actuated injection pump comprising a body having a cylindrical bore therein, a piston movable in said bore and defining a pair of chambers, an inlet for high pres-

sure liquid communicating with one of said pair of chambers, a nozzle communicating with the other of said pair of chambers, a passageway interconnecting said chambers, normally open valve means for closing said passageway, normally closed valve means for opening said inlet, means for operating said valve means substantially simultaneously, and resilient means in said other chamber for resiliently resisting movement of said piston by said high pressure liquid.

7. A fluid pressure actuated injection pump comprising a body having a bore therein, a piston movable in said bore and defining a pair of chambers, rotatable stop means for positioning said piston to determine the initial volume of said pair of chambers, an inlet for high pressure fuel communicating with one of said pair of chambers, the other of said pair of chambers having a fuel ejection orifice, a passageway interconnecting said chambers, normally open valve means for closing said passageway, normally closed valve means for opening said fuel inlet, means for operating said valves substantially simultaneously, resilient means in said other chamber biasing said piston toward said stop means, and frictionless bearing means abutting one end of said resilient means to facilitate operation of said stop means.

8. In a fluid injection system, an injection pump comprising a body having a chamber including an ejection orifice, a piston movable in said chamber to eject fluid from said chamber through said orifice, a source of fluid at a substantially constant high pressure, means for filling said chamber with fluid from said source at a pressure less than the said pressure of said source, and means to connect said source of fluid pressure to one side of said piston whereby said piston moves to eject fluid through said orifice.

9. In a fluid fuel injection system, a source of fluid fuel under substantially constant high pressure, an injection pump comprising a body having a chamber including an ejection orifice, a piston movable in said chamber, means for filling said chamber with fluid fuel from said source at a reduced pressure, and means for connecting said source of fluid fuel under pressure to one side of said piston whereby said piston moves to eject fuel through said orifice.

10. In a fuel injection system, a source of fuel under pressure, an injection pump comprising a body having a chamber including an ejection orifice, a piston movable in said chamber, rotatable stop means for positioning said piston to determine the volume of said chamber, means for filling said chamber with fuel from said source at a reduced pressure, and means for selectively connecting said source of fuel under pressure to the side of said piston opposite said chamber whereby said piston moves to eject fuel through said orifice.

11. In a fuel injection system, a source of fuel under pressure, a fuel injection pump comprising a body having a cylindrical bore, a piston movable in said cylindrical bore and defining a pair of chambers, one of said pair of chambers communicating with said source of fuel and the other of said pair of chambers having a fuel ejection orifice, means for filling said other chamber with fuel from said source, valve means for controlling the communication of said source of fuel under pressure to said one chamber, and means for operating said valve whereby said piston is moved by said fuel under pressure to eject fuel from said other chamber through said orifice. 75

12. In a fuel injection system, a source of fuel under pressure, a fuel injection pump comprising a body having a cylindrical bore, a piston movable in said bore and defining a pair of chambers, normally closed valve means for connecting said source of fuel to one of said pair of chambers, the other of said pair of chambers having a fuel ejection orifice, normally open valve means for filling said other chamber with fuel from said source, and means for operating said valve means substantially simultaneously, whereby said piston is moved by said high pressure fuel to eject fuel through said orifice.

13. In a fluid injection system, a source of fluid under pressure, a fluid injection pump comprising a body having a cylindrical bore, a piston movable in said cylindrical bore and defining a pair of chambers, normally closed valve means for connecting said source of fluid to one of said pair of chambers, the other of said pair of chambers having a fluid ejection orifice, normally open valve means for filling said other chamber with fluid from said one chamber, and means for operating said valve means substantially simultaneously whereby said piston is moved by said fluid under pressure to eject fluid through said orifice.

14. In a fuel injection system, a source of fuel under pressure, a fuel injection pump comprising a body having a cylindrical bore, a piston movable in said cylindrical bore and defining a pair of chambers, normally closed valve means for connecting said source of fuel to one of said pair of chambers, the other of said pair of chambers having a fuel ejection orifice, a passageway interconnecting said pair of chambers for filling said other chamber with fuel from said one chamber, normally open valve means for closing said passageway, and means for operating said valves substantially simultaneously whereby said piston is moved by said fuel under pressure to eject fuel through said orifice.

15. In a fluid injection system, a source of fluid under pressure, a fluid injection pump comprising a body having a cylindrical bore, a piston movable in said cylindrical bore and defining a pair of chambers, normally closed valve means for connecting said source of fluid to one of said pair of chambers, the other of said pair of chambers having a fluid ejection orifice, a passageway interconnecting said pair of chambers for filling said other chamber with fluid from said one chamber, a pressure relief chamber associated with said passageway, normally open valve means for closing said passageway, and means for operating said valves substantially simultaneously whereby said piston is moved by said fluid under pressure to eject fluid through said orifice.

16. In a fuel injection system, a source of fuel under pressure, a fuel injection pump comprising a body having a cylindrical bore, a piston movable in said cylindrical bore and defining a pair of chambers, rotatable stop means for positioning said piston to determine the respective initial volumes of said pair of chambers, normally closed valve means for connecting said source of fuel to one of said pair of chambers, the other of said pair of chambers having a fuel ejection orifice, a passageway interconnecting said pair of chambers for filling said other chamber with fuel from said one chamber, normally open valve means for closing said passageway, and means for operating said valves substantially simultaneously, whereby said piston is moved by said fuel under pressure to eject fuel through said orifice.

17. In a fuel injection system, a source of fuel

under pressure, a fuel injection pump comprising a body having a cylindrical bore, a piston movable in said cylindrical bore and defining a pair of chambers, rotatable stop means for positioning said piston to determine the respective initial volumes of said pair of chambers, normally closed valve means for connecting said source of fuel to one of said pair of chambers, the other of said pair of chambers having an ejection orifice, a passageway interconnecting said pair of chambers for filling said other chamber with fuel from said one chamber, a pressure relief chamber associated with said passageway, normally open valve means for closing said passageway, and means for operating said valves substantially simultaneously, whereby said piston is moved by said fuel under pressure to eject fuel through said orifice.

18. In a fuel injection system, a body having a cylindrical bore, a piston in said cylindrical chamber movable between first and second positions to define first and second chambers varying in volume with said piston movement, a high pressure source of fuel, normally closed valve means for connecting said high pressure source of fuel to said first chamber, said second chamber having a fuel ejection orifice, a passageway interconnecting said first and second chambers, normally open valve means for closing said passageway, said passageway and chamber being substantially filled with fuel, means for operat-

5
10
15
ing both said valve means substantially simultaneously whereby said piston is moved by high pressure fuel from said source to said second position effecting the ejection of fuel from said second chamber through said orifice, and resilient means in said second chamber for returning said piston to said first position when said valve means return to respective normal positions whereby said second chamber is filled with fuel through said interconnecting passage from said first chamber.
